GAME AND APPARATUS THEREFOR

Harry Amsterdam, Falls Church, Va.

Application October 21, 1937, Serial No. 170,286

1 Claim. (Cl. 273—135)

This invention relates to a game and more particularly to a game which may be played by a number of persons and wherein the termination of and winning of the game depends upon chance removal of counters from a quantity thereof placed in a box or other container. It will thus be seen that the game is entirely controlled by chance and each player is equally liable to win or lose.

10 It is another object of the invention to provide a chance controlled game wherein the person drawing the counters from the container plays against all of the other players and may win or lose from one or all of the other players according to chance removal of the counters from the container.

Another object of the invention is the provision of a game apparatus consisting of an improved arrangement of cards and counters together with indicators to be placed upon the cards in accordance with predetermined wishes of the players, the markings of the cards, counters and indicators being such that as the counters are removed at random from the container record 25 thereof may be accurately kept by all of the players.

Another object of the invention is to provide a game wherein during play by a number of players termination of the game with respect to 30 one player will not completely end the game as the others may continue the game until all of the counters are removed from the container.

Still another object of the invention resides in providing a device which is simple and durable in 35 construction, inexpensive to manufacture and one which will be very efficient in operation and application to use.

With these and numerous other objects in view, my invention consists in the novel features of 40 construction, combination and arrangement of parts as will be hereinafter referred to and more particularly pointed out in the specification and claim.

The invention is illustrated in the accompanying drawings wherein:

Figure 1 is a view of one of the cards distributed to the players by the master player;

Figure 2 is a fragmentary view showing one end portion of a master card used by the master 50 player;

Figure 3 is a side elevation of a set of chips or counters stacked upon a holder upon which they are placed when not in use during playing of the game;

55 Figure 4 is a view showing the chips of Figure 3

in vertical section and the holder in elevation; Figure 5 is a group view of a set of chips removed from a holder;

Figure 6 is a group view of a set of tokens used to indicate predetermined plays selected by players other than the master player; and

Figure 7 is a view of a blank or order slip used during playing of the game.

This game is based upon fluctuating values such as occur in the stock market by increases 10 or decreases in the value of certain stocks and during playing of a game one player who may be referred to as the master player represents a stock broker while the other players represent customers. The card 1 used by the master player 15 and the cards 2 used by the customers are duplicates except that the master card 1 is of greater dimensions than the customer's cards. This is in order that the master card may be easily distinguished from the player's cards and also to 20 permit the master player to easily apply chips to the master card. The master card and each of the player's cards is marked with a plurality of horizontally extending lines and vertically 25 extending lines which intersect and divide the face of the card into a plurality of horizontally 30 extending rows of spaces. The rows of spaces are designated by letters of the alphabet which are printed at opposite ends of the card and in the present illustration are the letters "A" 30 through "J", the letters at the left hand end of the card being accompanied by a minus mark and the letters at the right hand end of the card being accompanied by a plus mark. These letters are printed in the first and last vertical columns 35

3 and 4 of the card as shown in Figure 1 and the letters of the master card are printed in contrasting colors as clearly shown in Figure 2 in order that they may be easily distinguished from each other. While ten horizontally extending rows of spaces have been shown in the drawings it is to be understood that any number desired may be provided. Each row of spaces contains nineteen spaces between the spaces 3 and 4 marked with the letters, the spaces of the center 40 column 5 being marked with the numeral "10" and the spaces of the columns 6 between this center column and the end columns being marked with the numerals "1" through "9" respectively. All of the numerals of each horizontally extending 45 row of spaces are enclosed in a colored circle 7 corresponding in color to the color of the letters in the end columns 3 and 4 of the master card and the numbers 8 in the columns at the left of the column 5 are accompanied by a minus 50 55

sign 9 while the numbers 10 in the columns to the right of the center column are accompanied by plus signs 11. The numerals "10" in the spaces of the center column 5 represent the par value of stocks which are indicated by the letters in the columns 3 and 4 and the numerals in the columns between the center column and the end columns 3 and 4 indicate changes in the value of the stocks which may be losses or gains according to 10 whether the numerals are accompanied by minus or plus signs. The name of the game which may be "Par" as shown at 12 is printed at the top of the card, and at the top of the card there have also been printed minus and plus signs 13 and 14 15 accompanied by descriptive words as shown at 15 and 16. By so marking the card a player may select certain stocks to be dealt in and easily distinguish them by their colors and keep track of losses and gains in a manner to be hereinafter 20 set forth.

Companion to each horizontal row of spaces is a set of chips or counters illustrated in Figure 5 and consisting of nineteen chips. These chips are marked with letters 17 and colored as shown 25 at 18 to indicate the stocks to which they refer, the color of each set corresponding to that of the horizontal row bearing a similar letter upon the cards. One of the chips which is indicated by the numeral 19 bears the word "Par" as shown 30 at 20 together with the letter "A" and a color marking 21. The other chips are of two groups 22 and 23, the chips of the group 22 bearing minus signs as shown at 24 and the chips of the group 23 having plus signs 25 thereon. There 35 are nine chips to each group and they are numbered "1" to "9" respectively as shown at 26 and 27. These chips are to be handled by the master or "broker" who directs the game and placed upon the master card as they are drawn 40 at random from a bag or box in which they are placed and shaken before being drawn out, and since the markings of the chips correspond to the markings of the spaces upon the master card they can be quickly set in their proper places upon the master card by the "broker" and the 45 "customers" can easily identify corresponding spaces upon their cards and place check markers thereon which may be small pieces of colored card-board, grains of corn, or the like. An opening 28 is formed at the center of each chip and in order to carry the chips when they are not in use and easily determine whether all of the chips of a set are present there has been provided for 50 each set a carrier consisting of a base plate 29 from which rises a centrally located pin 30. In view of the fact that the pin is of such length that the stack of chips will be flush with the upper end of the pin when all of the chips are 55 upon the carrier it can be very easily determined 60 whether all of the chips of a set are upon a carrier or certain of the chips misplaced.

There have also been provided sets of tokens which are in possession of the broker at the start of the game and delivered by him to the various 65 purchasers as an initial move in starting play. These tokens which are indicated by the numerals 31 and 32 are illustrated in Figure 6 and referring to this figure it will be seen that the tokens are colored to correspond to the stocks they 70 represent and identified by the letters 33. The letters of the group of tokens 31 are each accompanied by a minus sign 34 and the letters of the group of tokens 32 are accompanied by plus signs 35. Tokens companion to all of the stocks are 75 provided, plus and minus tokens for each stock

being included, and while only one of each of the tokens has been shown in Figure 6, it is to be understood that a large number of each will be provided so that the broker can supply each customer with the proper tokens to indicate the stocks dealt in by the customer. Each customer can deal in any one or all of the various stocks. 5

When the customers order stocks a record must be kept of the same and in order to do so each customer will be furnished with an order slip 10 removed from a pad in the possession of the broker. Each of these order slips is printed with duplicate columns 37 and 38 of letters "A" through "J" accompanied by minus and plus signs and followed by dotted lines so that the customers 15 can write their orders upon the slips opposite the selected letters. If a customer or player wishes to play a certain stock "short" he writes his order after the appropriate letter followed by a minus sign whereas if he wishes to play 20 stock "long" he writes the order after the letter followed by the plus sign. Any customer, or player, may play any stock "long" or "short", but he may not play the same stock both "long" and "short", although he may if he desires, play 25 one stock "long" and some other "short". Two columns of letters are provided upon the order slip as the slip is to be torn along the dotted line 39 and one half of the slip kept by the broker and the other half returned to the customer together with tokens corresponding to the order. 30 Only one token of each stock is delivered to the customer as the tokens are to merely indicate the stocks ordered and not the quantity, this being shown upon the order slip. The tokens after being received by the customer are to be checked with his portion of the order slip and then placed in the spaces of the center column 5 of his card 2 where they remain as indicators 35 that he is playing certain stocks. The broker decides whether the game is to be "limited" or "unlimited". By this is meant whether a customer may purchase not more than a certain number of shares of any one stock or in an 40 unlimited game purchase as many shares as desired. 45

The par value of each stock is 10, whether it be 10 cents or 10 dimes or 10 anything. Each point won or lost represents one decimal of the par value of each share of stock and each digit represents the number of points won or lost. Thus, if the par value of any stock is 10 cents, then number one amounts to one cent, number 2 amounts to 2 cents, number 9 amounts to 9 cents, etc. The total gains on a certain stock is represented by the total of digits won minus the total of digits lost. Thus, for instance, if a certain stock played long has the chips numbered 3+, 5+, and 8+, then the total gain would be 16 points; or at par value of 10 cents it would amount to 16 cents. On the other hand, if before the stock is finished playing, there were also drawn the numbers 2- and 4-, then there would be a deduction of 6 points, and the net gain would amount to 10 cents. This method of calculation holds true also for losses, as will become clear with the following. 50 55 60 65

After the broker has returned to the customers their parts of the order slips and has furnished them with tokens, he then puts the chips in the bag, box or container provided for that purpose and shakes them up well, so that the chips are thoroughly mixed. Of course, if a certain stock is not played at all, then the chips for that stock need not be used, and they should be left on the holder. The 70 75 80 85 90 95

broker then, without looking to see what chips he is drawing, inserts his hand in the container and draws the chips one by one, calling out the letter, number and plus or minus sign of each 5 chip after drawing it out of the container. For example, A1+, C3-, E6+, etc. Each customer who happens to play the stock, no matter whether he plays that stock long or short, represented by the chip called by the broker, covers up that 10 number on his card with a piece of black cardboard paper provided for that purpose, or with anything else handy, such as a grain of corn etc. The broker keeps on calling the chips until he 15 draws out a chip with the inscription "Par" on it, let us say H Par. That stock is then called off the board and there is the pay-off or settlement. Let us see then what are the possible results.

Suppose, before the H Par chip was called, 20 there were called already the chips H1+, H4+, and H9+. That would amount to a total gain, to those who played H stock long, of 21 points, or 21 cents at a par value of 10 cents per share of stock. Now suppose, before the chip H Par was 25 called, there were also drawn the chips H2-, H5-, and H6-, or a total loss to those who played long of 13 points. The net gain, therefore, to those who played H stock long would be 21-13=8 cents per share, which amount they 30 are to collect from the broker. On the other hand, those who played H stock short would lose 8 cents, which amount they must pay to the broker. The net result would be a gain of 8 cents to those who played long, a loss of 8 cents 35 to those who played short and neither gain nor loss to the broker.

Suppose, however, before calling the chip H Par, there were called the chips H1-, H4-, H7- and H9-; also H2+, H5+ and H6+. Those who 40 played H stock short would then win 8 cents per share, those who played H stock long would lose 8 cents per share, while the broker would neither win nor lose anything.

Suppose, however, the chip H par is called, 45 and there results a net gain to those who played that stock short, but at the same time no customer played that stock long, then the loss is borne entirely by the broker; conversely, if no one played that stock short, then the net gain 50 goes entirely to the broker, while those who played that stock long are the only losers.

As a corollary from the above it follows that if all the plus and minus chips of a stock are called and the Par chip of that stock is called 55 last, then neither the customers, whether they play that stock long or short, nor the broker, either win or lose anything.

As a second corollary it would follow that the maximum gain or loss on any one stock possible 60 to any customer or the broker would amount to a total of 35 points per share and, of course, in an "unlimited" game or game with a high limit, where, let us say, a customer has ordered 10 shares of a certain stock, the gain or loss would 65 be ten times as much. The gain or loss, however, of 35 points on any stock could occur only on rare occasions, since it could only occur in such instances when either all the chips with a plus sign only or all the chips with a minus sign 70 only have been drawn before the drawing of the Par chip.

As a third corollary it would follow that in case all the stocks on the card are played, both long and short, and for an equal number of 75 shares of each stock, then the broker could not

win anything, but neither could he lose anything.

To sum it up: The game of Par was so designed that the chances for gain or loss, either to any customer or the broker, are mathematically 5 equal.

When the broker draws the Par chip of any stock, he calls again all the chips of that stock previously drawn and found on his master card, so as to enable his customers to check up their 10 cards against the numbers thus drawn for any possible error. The account for that stock is then closed and payment is then and there made to whomever due and collected from whomever due. The customers then remove the token and 15 "covers" of the black pieces of cardboard paper from the numbers for that stock, and the broker removes the chips for that stock from his master card and puts them back on the rod. He then proceeds with the drawing and calling of chips 20 for the remaining stocks in the same manner. Any chips still left in the container of stock of which the Par chip had already been drawn, and is drawn by the broker in the process of drawing chips for stocks which are still in the course of 25 being played, are announced by the broker as: "Chip of played stock"; whereupon he puts that chip back on the rod. He then continues drawing and calling chips until all the stocks from A to J have been played.

At least one numbered chip of a certain stock must be drawn first before the Par chip of the same stock may be called. In case the Par chip of a certain stock happens to be drawn previous to the drawing of any numbered chip of the same 35 stock, then such Par chip is not called, but is returned to the container and is called only when drawn again after one or more chips of the same stock had been drawn and called.

A modified form of this game may be played at 40 house parties, where the host or hostess provides prizes for the players. The maximum number of players who can play this modified form of the game is 20. In this modified game, however, no order slips are needed, twenty of the tokens are 45 drawn by the players, of which ten of the tokens are from A+ to J+ and ten of the tokens are from A- to J-. Each participant in the game draws one token and plays one share of one stock only, which is either plus or minus (long or short) and 50 corresponds to the token the prospective player has drawn, such as A+ or B-, or whatever token the player has drawn. The host or hostess acts in such game as broker, which in this modified form of the game is called "referee". The referee, 55 of course, does not compete for a prize. The game from then on is played similarly as described in the foregoing: When a Par chip is drawn there is recorded the gain or loss to the player playing that stock long (+) and to the player playing 60 that stock short (-). After all the chips have been played, the player who won most points gets the first prize, and the player who lost most points gets the "booby" prize. As far as the manner of awarding of prizes is concerned, the host or 65 hostess may modify the above suggestion to his or her liking.

In case there are less than twenty players, let us say, only eight players, then four stocks and four corresponding sets of chips are played, say 70 from A to D, and the tokens from A+ to D+ and from A- to D- are drawn by the players for places or stocks. The host as referee puts the chips A to D in the container and draws the chips therefrom as previously explained. The 75

rest of the procedure is the same as given under the paragraph above. For any other number of players less than twenty the proportion of stocks, chips and tokens is accordingly.

5 In case the players are made up of an odd number, say seven players, then the game proceeds as above, with an even number of stocks, chips and tokens, as described before; namely, four stocks are played, four sets of chips are drawn and four corresponding tokens with a plus sign and four corresponding tokens with a minus sign are drawn by the prospective players. It is true that there is an extra token, but this is only used to determine whether the odd player should play 10 his stock long or short; otherwise it does in no way effect the outcome of the game differently than if there were an even number of players.

Another modified form of the Par game is for 20 players to pair off against each other on the basis of long players and short players. This form of the game is in most respects similar to those previously described; namely each player plays only one stock, decided by drawing a token whether it is to be long or short; but, instead of competing 25 for a prize, the players pair off, and each player playing a certain stock long plays against an opponent who plays the same stock short. In this form of the game the winner playing a certain stock collects directly from his opponent. In case 30 there is an odd number of players, then the broker or referee pairs off as opponent to the odd player, and uses his master card also as a player's card.

From the foregoing description of the construction of my improved device, the operation thereof 35 and the method of applying the same to use will be readily understood. It will be seen that I have provided a simple, inexpensive and efficient means for carrying out the objects of the invention and while I have particularly described the elements

best adapted to perform the functions set forth, it is obvious that various changes in form, proportion and in the minor details of construction may be resorted to, without departing from the spirit or sacrificing any of the principles of the 5 invention.

Having thus described the invention, what is claimed is:

Game apparatus comprising a master card, a plurality of player's cards, said cards being each 10 provided with horizontal rows of spaces having therein scoring symbols, the symbols of each row being clearly distinguishable from the symbols of other rows and arranged in horizontally extending groups of progressively different values, the values of one group being accompanied by plus signs and representing increasing values and those of a second group being accompanied by minus signs and representing decreasing values, one symbol of each row being located between the groups of the 15 said row and being of a higher value than the symbols of either group and constituting par value, a plurality of sets of identifying tokens, the tokens of each set bearing identification symbols companion to the symbols of one row of spaces of 20 a card, said tokens being of a size adapting them to be deposited upon the spaces of a player's card bearing Par markings, order slips each provided with a scoring line adapting it to be divided into sections, each section of an order slip having 25 thereon identifying symbols corresponding to the symbols of the tokens and also having spaces opposite the symbols to receive notations relating to transactions in the game, and a plurality of sets of chips, the chips of each set bearing symbols corresponding to the symbols in the spaces of one row of spaces of a card.

HARRY AMSTERDAM.
